(57) **CLAIM**

I claim the ornamental design for a stand for supporting a computing device, as shown.

DESCRIPTION

FIG. 1 is a top front isometric view of a stand for supporting a computing device in a collapsed configuration in accordance with the present design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

1 Claim, 3 Drawing Sheets
